UNITED STATES PATENT OFFICE.

BANCROFT G. BRAINE, OF NEW YORK, N. Y., ASSIGNOR TO THE RAIL JOINT COMPANY,
OF NEW YORK, N. Y., A CORPORATION OF NEW YORK.

RAIL-JOINT.

1,191,557.

Specification of Letters Patent. Patented July 18, 1916.

Application filed March 27, 1916. Serial No. 87,038.

To all whom it may concern:

Be it known that I, BANCROFT G. BRAINE, a citizen of the United States, residing at New York city, in the county of New York 5 and State of New York, have invented certain new and useful Improvements in Rail-Joints, of which the following is a specification.

This invention relates to rail joints, and 10 more particularly to a novel improvement in joints of the base supporting type.

To this end, the invention has in view a joint bar combining the practical features of the well-known continuous type of rail joint, 15 and a supplemental base reinforcement therefor, which not only stiffens and reinforces the continuous rail base support, but also provides added strength and rigidity at the center of the joint. These desirable results are attained by a novel double 20 or plural base construction, wherein all of the metal is utilized to its maximum effect, and which obviates wastage of metal by shearing as is required in some forms of 25 construction.

With the above and other objects in view which will more readily appear as the nature of the invention is better understood, the same consists in the novel construction, combination and arrangement of parts herein-after more fully described, illustrated and claimed.

A preferred and practical embodiment of the invention is illustrated in the accompanying drawings, in which—

Figure 1 is a side elevation of a rail joint including a joint bar embodying the novel characteristics indicated. Fig. 2 is a side elevation of the joint bar shown in Fig. 1 40 before the punching of the bolt holes, and before displacing the ends of the supplemental reinforcing member into final position. Fig. 3 is a projected end view of the bar of Fig. 2. Fig. 4 is a vertical sectional view on the line 4—4 of Fig. 1 at the center of the joint. Fig. 5 is a vertical sectional view on the line 5—5 of Fig. 1 near the end of the joint.

Similar reference characters designate 50 corresponding parts throughout the several figures of the drawings.

The improvement contemplated by the present invention is applicable to any type of rail joint bar having a rail supporting base member, but possesses special utility 55 of the particular operation described, the ef-

in connection with a joint bar having the general characteristics of the continuous type of bar which includes in its construction the upright web member 1, the head member 2 underlying the head of the rail, 60 the foot flange 3, and the horizontal inwardly extending rail supporting base portion 4 which is integrally united with the foot flange as at α . Thus, the present invention preferably retains the essential characteristics of the continuous type of joint bar, but, as indicated, has special reference to an improvement in the base portion of the bar in order to obtain additional reinforcement for the primary rail supporting 65 base member, as well as added reinforcement and stiffness at the center of the joint. Accordingly, in constructing a rail joint bar having the present invention, the base portion 4 of the bar is formed with two members, 70 namely, the primary base member 5 and the supplemental base member 6. The primary base member 5 extends continuously throughout the joint and constitutes a continuous rail seating member, and the supplemental base member 6 is caused to assume 75 such a position as to provide the strengthening and reinforcing effect referred to. During the course of manufacturing the bar it reaches the nearly finished condition shown 80 in the outline Fig. 3 of the drawings. In this condition the bar is entirely completed as to its upper portions above the rail flange, and is also completed as to its base portion 4 with the exception of bending or bull-doing 85 the supplemental base member 6 into its final position. This latter operation affects the 90 opposite end portions 7 only of the supplemental base member, so that such end portions are displaced, from a position spaced 95 a distance from the main base member 5, into a horizontal plane parallel with and meeting the plane of the primary or main rail seating base member 5. Accordingly, the bending or bull-doing operation, which 100 displaces the end portions of the supplemental base member into reinforcing and supporting engagement with the end portions of the primary base member 5 leaves an intermediate depending girder flange 8, bearing a divergent relation to the primary or main base member and thereby producing a stiffening or reinforcing member at the central portion of the joint bar. By reason 105 of the particular operation described, the ef-

fect of the displacement of the end portions of the supplemental base member produces an arched connecting web of metal 9 integrally connecting the inwardly and downwardly inclined girder flange 8 with the end supporting members 7 of the supplemental base member.

With particular reference to the novel features of the supplemental base member 6, 10 it will be observed that the same is preferably provided at its edge with an enlargement of metal which constitutes a reinforcing bead 10 for giving increased strength and rigidity to the said member of the plural or divided base portion. In order to provide increased effectiveness for the supplemental base member, the same is preferably of greater width than the rail seating member so that the bead 10 formed at the 15 edge thereof may have a bearing contact with the underside of the rail bases when the ends of the reinforcing member are bent upwardly into a horizontal plane. That is to say, since the supplemental base member is 20 of greater width than the primary base member, the reinforcing bead 10 will extend over the inner edge of the primary base member 5 when the ends 7 of the supplemental base member are bent up into a plane 25 parallel to the primary base member. Thus, in addition to the support afforded by the continuous rail seating member 5, the bases of the rails are provided with additional support from the supplemental reinforcing 30 member through the medium of the reinforcing bead 10 which is adapted to directly contact therewith. In this way, the supplemental reinforcing member performs the two-fold function of supporting the continuous rail seating member and the rail bases, thus more effectively distributing the load 35 on the joint bar and carrying the same into the girder flange 8 where the greatest trussing effect is obtained.

40 Without further description, it is thought that the many features and advantages of the present invention will be readily apparent, and it will also be understood that various changes in the form, proportion, and 45 minor details of construction may be resorted to without departing from the spirit of the invention or scope of the appended claims.

I claim:

- 55 1. A rail joint including a joint bar having a rail seating base member and a supplemental reinforcing member in supporting contact therewith.
2. A rail joint including a joint bar having a rail seating member and a supplement-

tal reinforcing member having a depending girder flange, and also in supporting contact with the rail seating member.

3. A rail joint including a joint bar having a rail seating member and a supplemental reinforcing member having a central depending girder flange, and also in supporting contact with the rail seating member.

4. A rail joint including a joint bar having a divided base portion including an upper continuous rail seating member, and a lower supplemental reinforcing member.

5. A rail joint including a joint bar having a divided base portion including a rail seating member and a supplemental reinforcing member having its end portions engaging the rail seating member and its central portion spaced therefrom.

6. A rail joint including a joint bar having a divided base portion comprising a continuous rail seating member and a supplemental reinforcing member having a depending girder portion at the center, and also in supporting contact with the rail seating member.

7. A rail joint including a joint bar having a divided base portion comprising a continuous rail seating member and a supplemental reinforcing member having a depending girder portion and end portions in supporting contact with the rail seating member, said reinforcing member also having arched truss portions connecting the girder portion with the end portions.

8. A rail joint including a joint bar having a divided base portion comprising a continuous rail seating base member and a supplemental reinforcing member underlying the rail seating member and having a reinforcing bead at its edge.

9. A rail joint including a joint bar having a divided base portion comprising a continuous rail seating base member and a supplemental reinforcing member underlying the rail seating member and having a continuous reinforcing bead at its edge, and also having a depending girder flange portion.

10. A rail joint including a joint bar having a continuous rail seating base member, and a supplemental base member having end portions in supporting contact with the rail seating member, a central depending reinforcing girder, and webs integrally connecting said girder and end portions.

In testimony whereof I hereunto affix my signature in the presence of two witnesses.

BANCROFT G. BRAINE.
